UNITED STATES PATENT OFFICE.

HUNT DIEDERICH, OF NEW YORK, N. Y.

DESIGN FOR AN ELECTRIC LAMP AND FAN.

54,392.

Specification for Design.

Patented Feb. 10, 1920.

Application filed June 16, 1919. Serial No. 304,704. Term of patent 14 years.

To all whom it may concern:

Be it known that I, HUNT DIEDERICH, a citizen of the United States, residing at New York city, in the county of New York and State of New York, have invented a certain new, original, and ornamental Design for an Electric Lamp and Fan, of which the following is a specification, reference being had to the accompanying drawing, forming part thereof.

In the drawings, Figure 1 is a front ele-

vation showing my new design, the base being broken away. Fig. 2 is a side elevation partly in section of the same. In both views of the drawings, the fence is shown down in dotted lines.

I claim:

The ornamental design for an electric lamp and fan, as shown.

In testimony whereof I have hereunto set my hand.

HUNT DIEDERICH.
